Fig 8

FIG. 1 is a right rear perspective view of a top for pickup truck showing our new design;

FIG. 2 is a left rear perspective view thereof, with the door in open position;

FIG. 3 is a top plan view thereof;

FIG. 4 is a left side elevation view thereof;

FIG. 5 is a right side elevation view thereof with the door in open condition;

FIG. 6 is a rear elevation view thereof;

FIG. 7 is an enlarged detail section view taken along the line 7—7 of FIG. 5;

FIG. 8 is an enlarged detail section view taken along the line 8—8 of FIG. 6;

FIG. 9 is an enlarged detail section view taken along the line 9—9 of FIG. 3.

We claim:

The ornamental design for a top for pickup truck, as shown and described.
